UNITED STATES PATENT OFFICE.

DAVID GOODWILLIE, OF CHICAGO, ILLINOIS.

EGG-CARRIER.

SPECIFICATION forming part of Letters Patent No. 249,753, dated November 22, 1881.

Application filed May 28, 1881. (No model.)

To all whom it may concern:

Be it known that I, DAVID GOODWILLIE, of Chicago, in the county of Cook and State of Illinois, have invented a new and useful Improvement in Egg-Carriers, of which the following is a specification, reference being had to the accompanying drawings, illustrating the improvement, in which—

Figure 1 is a top or plan of an egg-carrier embodying my improvement; Fig. 2, a side elevation thereof; Fig. 3, a sectional elevation of one egg-pocket and an egg represented therein. Fig. 4 shows the position of the slats when folded. Fig. 5 is a broken elevation of one of the main strips, showing one form of diagonal slot to receive the cross-strip; Fig. 6, a broken elevation of one of the cross-strips, showing the slot through which the tongue of the main strip passes.

The nature of the present invention consists in the combination of the main slats of the carrier, provided with horizontally-enlarged vertical or inclined slots, and tongues extending longitudinally across the slots, in connection with transverse slats put through the upper portion of the main slats to support the upper portions of the eggs, and slats put through the elongated slots in the lower portion of the main slats, and hung to tongues to incline laterally and adjust themselves to the form of those portions of the eggs with which they come in contact and impart a yielding support therefor, as the whole is hereinafter fully described and shown.

A represents the main slats, which form two sides of the egg-pockets.

B are the upper transverse slats, which form the two sides of the top parts of the pockets, at right angles to the slats A.

C represents the lower transverse slats, which form the bearings to support the eggs. The slots I, through which the upper slats pass, are simply wide enough for slats B readily to

be inserted therein; but the lower slots, J, are so wide as will allow the slats therein to, in 45 cross-section, set at right angles to the slats A, and to be so inclined as to substantially fit the form of the egg at such a distance from its apex as to give it an easy support, and for this purpose the lower tongues on the main slats 50 are made so much narrower than the slots g, through which they pass, as to allow the slats C readily to turn laterally.

Different forms of tongues, b, b', and d, may be employed to attain a like result in uniting 55 the parts.

The tongues are not new in this application; neither are such slots as will hold the upper and lower strips vertical, as they have before been used.

The diagonal slot K at figure B B, which has inclined margins to support the slats or strips when eggs are placed on them, and which allows the slat to assume vertical positions when the several parts of the carrier are shut together, I consider new, as I do also the slots J, which allow the lower transverse slats to have 65 a like position.

It will be understood that the tongues pass through slots g in the transverse slats C, by 70 which means the egg-pockets have in the plan rectangular forms, as shown in Fig. 1.

I claim as new and desire to secure by Letters Patent—

In an egg-carrier, the combination of the 75 slat A, having the slots J and tongues d, with the slat C, having the slot g, the slots J and g being of different size relatively to the parts which they receive, to permit the slat C to rock from a vertical to an inclined position, as and 80 for the purpose set forth.

DAVID GOODWILLIE.
